UNITED STATES PATENT OFFICE.

GEORGE WILLIS DUNHAM, OF NEW YORK, N. Y., ASSIGNOR TO GRAHAM BROTHERS,
OF EVANSVILLE, INDIANA, A CORPORATION OF INDIANA.

DESIGN FOR A TRACTOR.

58,466.

Specification for Design.

Patented July 26, 1921.

Application filed March 29, 1920. Serial No. 369,755. Term of patent 7 years.

To all whom it may concern:

Be it known that I, GEORGE W. DUNHAM, a citizen of the United States of America, residing at New York city, in the county of New York and State of New York, have invented a certain new, original, and ornamental Design for a Tractor, of which the following is a specification, reference being had therein to the accompanying drawings, forming part thereof, in which—

Figure 1 is a side elevation of the tractor; Fig. 2 is a front elevation thereof; and Fig. 3 is a rear elevation thereof.

I claim:

The ornamental design for a tractor, substantially as shown.

GEORGE WILLIS DUNHAM.
